UNITED STATES PATENT OFFICE

111,690

DESIGN FOR A DEVICE FOR INVESTIGATING ATOMIC STRUCTURE

William H. Wells, Wilkinsburg, Pa., assignor to Westinghouse Electric & Manufacturing Company, a corporation of Pennsylvania

Application April 6, 1938, Serial No. 76,313

Term of patent 14 years

To all whom it may concern:

Be it known that I, William H. Wells, a citizen of the United States, residing at Wilkinsburg, in the county of Allegheny and State of Pennsylvania, have invented a new, original, and ornamental Design for a Device for Investigating Atomic Structure, of which the following is a specification, reference being had to the accompanying drawings forming part thereof.

Figure 1 is a front elevation and Fig. 2 is a side elevation of a device for investigating atomic structure showing my new design.

The dominant features of my design are shown in solid black lines in the drawings.

I claim:

The ornamental design for a device for investigating atomic structure, as shown and described.

WILLIAM H. WELLS.
